UNITED STATES PATENT OFFICE

GORDON E. ROEDDING, OF GRAND RAPIDS, MICHIGAN, ASSIGNOR TO GRAND RAPIDS BRASS COMPANY, OF GRAND RAPIDS, MICHIGAN, A CORPORATION OF MICHIGAN

LATCH

Application filed September 2, 1930. Serial No. 479,186.

The present invention relates to latches; and its object is, generally, to provide an improved structure of that character; and more particularly, to provide such a latch having a swingable latch bolt and lever handle and improved means for urging the latch bolt to its latching and retracted positions respectively, such structure comprising parts readily assembled.

This and any other and more specific objects hereinafter appearing are attained by, and the invention finds preferable embodiment in, the latch structure hereinafter particularly described in the body of this specification and illustrated by the accompanying drawings, in which:

Figure 1 is a front view of a latch and its keeper mounted on a door closure and its jamb respectively, the latch casing being sectioned on line 1—1 of Figure 3;

Figure 2 is a similar view of portions of the latch and casing sectioned on the same plane, but showing the parts in another position;

Figure 3 is a sectional view thereof taken on line 3—3 of Figure 1;

Figure 4 is a left-hand elevational view thereof, showing the closure partially open;

Figure 5 is a sectional view of the latch and casing taken on line 5—5 of Figures 1 and 2; and

Figure 6 is a view in perspective of the back plate of the latch casing and its forwardly extending parts.

In these drawings is illustrated a latch mounted on a swingable door closure 1 and its keeper 2 mounted on the frame or jamb 3 of the door. The latch has a casing 4 comprising a back plate 5 through whose holes 6 and registering holes 7 in the flanges of the casing the mounting screws 8 pass.

This back plate has a forwardly extending plate portion 9 and ears 10, 10. The latch bolt 11 extends through an opening 12 in plate portion 9, bearing in said opening, and is desirably formed of sheet metal bent to form a middle or web portion 13 and downwardly extending flanges 14, 14. A notch 15 is formed in the upper side of the latch bolt and constitutes a bearing in which it rocks

(between operative or latching position seen in Figure 1 and retracted position shown in Figure 2) on the upper edge 16 of the opening 12. The latch bolt is thus rocked by means of a lever handle 17 fulcrumed on a pivot pin 18 mounted in the openings 19, 19 of the forwardly extending ears 10, 10 of the latch casing's back plate 5. In registering notches 21, 21 in the under edges of the latch bolt's flanges 14, 14 bear the laterally extending lugs 22, 22 of a link bar 23 extending between said flanges and having a lug portion 24 bearing in a recess 25 in the middle or web portion 26 of the lever handle. This link bar 23 has a longitudinal slot 27 in which the pivot pin 18 slidably bears to guide said member in its movement, and has also lateral shoulders 28, 28 engaging the latch bolt at points opposite to the lugs 22, 22, so that the movement of the lever handle one way or the other will swing the latch bolt in opposite directions respectively.

A coiled expansion spring 29 is seated at its lower end around the upward lug 30 of plate portion 9, and at its upper end presses against the under edges of the lateral extensions 31, 31 of a rod 32 inside this spring, these extensions bearing at their upper edges in notches 33 in the lower edges of the latch bolt's flanges 14, 14.

As the latch bolt swings from one position to the other, this spring 29 passes through the opening 12 from one side to the other of plate portion 9, and thus urges the latch bolt to one or the other of its said positions.

It will be seen that the parts of this latch are of simple although strong construction, and that the same are readily assembled and disassembled.

The invention being intended to be pointed out in the claims, is not to be limited to or by details or construction of the particular embodiment thereof illustrated by the drawings or hereinbefore described.

I claim:

1. A latch structure comprising: a casing having an internal transverse portion with an opening therethrough; a latch bolt extending through said opening and bearing rockably at one edge on said portion; a lever

handle; a link bar connected to the latch bolt and to the lever handle to rock the bolt by the handle.

- 5 2. A latch structure comprising: a casing having an internal transverse portion with an opening therethrough; a latch bolt extending through said opening and bearing rockably at one edge on said portion; a lever handle; a link bar connected to the latch bolt and to the lever handle to rock the bolt by the handle; an expansion spring in said opening pressing the opposite edge of the latch bolt to urge the bolt to latching and retracted positions respectively.

- 10 15. 3. A latch structure comprising: a casing having an internal transverse portion; a latch bolt having spaced sides and at one edge a notch bearing rockably on said portion; a lever handle fulcrumed inside the casing; a link bar extending between said sides and connected to the latch bolt and to the lever handle to rock the bolt by the handle.

- 15 20. 4. A latch structure comprising: a casing having an internal transverse portion; a latch bolt having spaced sides and at one edge a notch bearing rockably on said portion; a lever handle fulcrumed inside the casing; a link bar extending between said sides and connected to the latch bolt and to the lever handle to rock the bolt by the handle; an expansion spring pressing the opposite edge of the latch bolt to urge the bolt to latching and retracted positions respectively.

- 25 30. 35. 5. A latch structure comprising: a casing having an internal transverse portion; a latch bolt having spaced sides and at one edge a notch bearing rockably on said portion; a lever handle fulcrumed inside the casing; a link bar extending between said sides and connected to the latch bolt and to the lever handle to rock the bolt by the handle; a coiled expansion spring containing a rod and pressing the same on the opposite edge of the latch bolt to urge the bolt to latching and retracted positions respectively.

- 40 45. 6. A latch structure comprising: a casing having an internal transverse portion with an opening therethrough; a latch bolt extending through said opening and having spaced sides, a notch at one edge bearing rockably on said portion, and a notch at its opposite edge; a lever handle fulcrumed inside the casing; a link bar extending between said sides, and connected thereto and to the lever handle to rock the bolt by the handle; a coiled expansion spring in said opening; a rod in the spring pressed thereby in the second-mentioned notch to urge the bolt to latching and retracted positions respectively.

- 50 55. 7. A latch structure comprising: a casing having an internal transverse portion with an opening therethrough; a latch bolt extending through said opening and having spaced sides, a notch at one edge bearing

rockably on said portion, and notches in said sides at its opposite edge; a lever handle fulcrumed on a pivot pin inside the casing; a link bar extending between said sides and connected thereto and to the lever handle to rock the bolt by the handle, and having a slot in which the pivot pin bears; a coiled expansion spring in said opening and pressing at one end on one side thereof; a rod surrounded and engaged by the spring and pressed thereby in the notches of said sides to urge the bolt to latching and retracted positions respectively.

80 70. 8. A latch structure comprising: a casing having an internal transverse portion; a latch bolt having at one edge a notch bearing rockably on said portion and spaced sides having pairs of registering notches at the opposite edge of the latch bolt; a lever handle fulcrumed on the casing; a link bar 85 extending between said sides and connected to the lever handle and having lateral lugs engaging in one pair of said notches to rock the bolt by the handle; a coiled expansion spring; a rod in the spring engaging in the other pair of said notches to urge the bolt to latching and retracted positions respectively.

9. A latch structure comprising: a casing having an internal transverse portion; a latch bolt having at one edge a notch bearing rockably on said portion and spaced sides having pairs of registering notches at the opposite edge of the latch bolt; a lever handle fulcrumed on the casing and having a recess; a link bar extending between said sides and having a lug engaging in said recess and lateral lugs engaging in one pair of said notches to rock the bolt by the handle; a coiled expansion spring; a rod in the spring engaging in the other pair of said notches to urge the bolt to latching and retracted positions respectively.

100 95. In testimony whereof I have hereunto set my hand at Grand Rapids, Michigan, this 28th day of August, 1930.

110 GORDON E. ROEDDING.
